O. M. BURTON.
MATTRESS AND THE LIKE.
APPLICATION FILED SEPT. 3, 1910.

977,508.

Patented Dec. 6, 1910.

UNITED STATES PATENT OFFICE.

OLIVER M. BURTON, OF CHICAGO, ILLINOIS.

MATTRESS AND THE LIKE.

977,508.

Specification of Letters Patent.

Patented Dec. 6, 1910.

Application filed September 3, 1910. Serial No. 580,386.

To all whom it may concern:

Be it known that I, OLIVER M. BURTON, a citizen of the United States, and a resident of Chicago, county of Cook, and State of Illinois, have invented certain new and useful Improvements in Mattresses and the Like, of which the following is a full, clear, and exact description.

The improvement relates to mattresses, 10 cushions and the like in which a series of spiral springs are employed to increase the resiliency of the mattress and maintain it in proper form.

The invention seeks to provide a simple 15 and effective means by which the spring construction on the mattress can be readily and economically assembled and which will serve to securely but flexibly hold the individual springs in position, so that they will maintain the proper shape of the mattress or 20 cushion and cannot cause a disagreeable grating sound as they are compressed or expanded.

The invention consists in the features of 25 improvement hereinafter set forth, illustrated in the preferred form in the accompanying drawings and more particularly pointed out in the appended claims.

In the drawings, Figure 1 is a plan view 30 of a corner of the improved mattress or cushion. Fig. 2 is a similar view with the upper layer of the filling material removed and the inner covering or casing, to which the springs are connected, exposed. Fig. 3 35 is a transverse section of the improved mattress. Fig. 4 is a cross section of a modified form.

The improved spring construction may be applied to mattresses or cushions of different 40 types, but is particularly applicable to hollow or self renovating mattresses such as shown in Figs. 1 to 3 inclusive, and to box springs having upholstered tops, such as shown in Fig. 4.

The mattress shown in Figs. 1 to 3 inclusive, comprises an outer tick or covering 1 of suitable flexible material or fabric, an inner casing or spring covering 2, and an intermediate filling 3 of pliable material. 50 The inner casing or covering 2 within which the spiral springs 4 are arranged is formed of stout flexible material, preferably burlap. The spiral springs 4 are preferably of the "hour glass" type and are arranged 55 within the inner casing or covering 2 in rows in the usual manner. The end coils 5 of

the spiral springs extend through the upper and lower layers of the inner casing or covering 2 and are secured thereto by flexible strips 6 which are woven through the end coils. The end coils 5, in the preferred form of the invention, are closed and the upper and lower layers of the casing or covering 2 are provided with a series of parallel slits 7 which are preferably arranged in pairs and through which opposite portions of each end coil extend, as most clearly shown in Fig. 2. The flexible strips 6 extend over the outer surfaces of the covering 2 and are woven through the portions of the end coils or rings 5 which extend through the slits 7 to thereby secure the springs at their upper and lower ends to the covering. The ends of the strips 6 are fastened to a suitable portion of the mattress and are 75 preferably secured to the inner covering 2 at the seam 8 (see Fig. 3), which unites the upper and lower layers of the casing or covering 2 at the edge of the mattress. This spring construction can be economically assembled, since the closed end coils or rings 5 of the springs can be readily inserted in the slits 7 and the strips 6 quickly woven therethrough. The strips are preferably 80 of a width nearly equal to the length of 85 the slits 7, so that the springs are securely held in position to thereby preserve the form of the mattress and to prevent any contacting and grating of the coils of the springs as they are compressed or expanded. The inner casing or covering 2 to which the ends of the springs are connected is 90 held in position by the quilting stitches 9 which unite it to the outer ticking and by a stitching 10 which extends through the 95 corners of the outer ticking and through the corners of the inner casing to form rounded upper and lower edge portions 11 of the mattress. The filling 3 may be of any suitable pliable material, such as cotton, hair or 100 other suitable fiber and is preferably arranged in layers extending around the inner casing or spring covering 2.

The box spring construction shown in Fig. 4 comprises a frame 12 of wood or 105 other suitable material having cross slats 13 to which the lower ends of the springs 4 are secured. The construction is provided with an upholstered top comprising an outer ticking 1', which preferably extends around the frame 12 and beneath the slats 13, an inner casing or spring covering 2' and an 110

intermediate filling 3'. The springs 4 are united to the inner covering 2' in the manner already described, that is to say, the closed end coils 5 extend through the slits 7 in the covering and flexible cross pieces or strips 6 and extend over the outer face of the covering and are woven through the end coils. In this construction the ends of the strips 6 and the edge of the covering 2' extend over and 10 are secured to a border rod 14 and are fastened to the frame 12.

The improved construction, as stated, can be economically assembled, is extremely durable and resilient and maintains the 15 shape of the mattress and the individual springs are held in proper position.

It is obvious that changes may be made in the details set forth without departure from the essentials of the invention as 20 defined in the claims.

I claim as my invention:—

1. In mattresses and the like, the combination with an upholstered top comprising an inner and outer flexible coverings and an 25 intermediate pliable filling, of a series of spiral supporting springs having their end coils extending through said inner covering, and flexible cross strips woven through said end coils to secure the same to said inner 30 covering.

2. In mattresses and the like, the combination with an upholstered top comprising an inner and outer flexible coverings and an 35 intermediate pliable filling, of a series of spiral supporting springs having their end coils extending through said inner covering, and flexible strips extending over the outer face of said inner covering and woven through said end coils.

40 3. In mattresses and the like, the combination with an upholstered top comprising an inner and outer flexible coverings and an intermediate pliable filling, of a series of spiral supporting springs having their end 45 coils extending through said inner covering, and flexible cross strips woven through said end coils, the ends of said cross strips and the edges of said inner covering being secured together and to said outer covering.

50 4. In a spring construction for mattresses and the like, a series of spiral springs, a flexible covering extending over said springs and having slits through which the end coils of said springs extend, and flexible 55 cross strips woven through said end coils, substantially as described.

5. In a spring construction for mattresses and the like, a series of spiral springs, a

flexible covering extending over said springs and having slits through which opposite 60 portions of each of the end coils of said springs extend, and flexible strips extending over the outer face of said covering and woven through said end coils.

6. In a spring construction for mattresses 65 and the like, a series of spiral springs having closed end coils, a flexible covering extending over said springs and having slits through which said end coils extend, and flexible strips woven through said end coils 70 to secure the same to said covering.

7. In a spring construction for mattresses and the like, a series of spiral springs having closed end coils, a flexible covering extending over said springs and having slits 75 through which opposite portions of each of said end coils extend, and flexible cross strips extending over the outer surface of said covering, and woven through said end coils.

8. In a spring construction for mattresses 80 and the like, a series of spiral springs having closed end coils, a fabric covering extending over said springs and having pairs of parallel slits through which opposite 85 portions of each of said end coils extend, and a series of parallel, wide, fabric strips extending over the outer face of said covering, woven through said end coils and suitably fastened at their ends.

9. A hollow mattress comprising a series 90 of spiral springs, an inner flexible casing or covering extending over said springs and through which the upper and lower end coils of said springs extend, a series of flexible cross strips woven through said end 95 coils to secure the same to said inner casing, an outer tick, a filling of pliable material between said tick and said inner casing, and stitching forming upper and lower rounded corners of the mattress and uniting said 100 outer tick and inner casing.

10. A hollow mattress comprising an outer tick, an inner flexible casing, an intermediate pliable filling, a series of spiral springs having closed end coils arranged within 105 said inner casing, the upper and lower layers of said inner casing having slits through which said end coils extend, and flexible strips extending over the outer surfaces of said inner covering, woven through said end 110 coils and fastened to said inner casing at their ends.

OLIVER M. BURTON.
